SPLASH GUARD

Robert G. Bode, 5664 N. Natoma Ave.,
Chicago, Ill. 60631

Filed Sept. 22, 1975, Ser. No. 615,674

Term of patent 14 years

Int. Cl. D12—16

U.S. Cl. D12—185

FIG. 1

FIG. 3

FIG. 2

FIG. 4

FIG. 1 is a perspective view of a splash guard embodying my new design;

FIG. 2 is a side elevational view thereof;

FIG. 3 is an end elevational view thereof; and

FIG. 4 is a bottom plan view thereof.

I claim:

The ornamental design for a splash guard, substantially as shown.
